UNITED STATES PATENT OFFICE

2,420,075

BUBBLE TRAY DOWNCOMER

Hans C. Glitsch, Dallas, Tex., assignor, by mesne assignments, to Glitsch Engineering Company, Dallas, Tex., a partnership consisting of Fritz W. Glitsch, Jr., and Hans C. Glitsch

Application June 23, 1945, Serial No. 601,149

8 Claims. (Cl. 261—114)

1

This invention relates to new and useful improvements in bubble tray downcomers.

One object of the invention is to provide an improved downcomer adapted to be mounted adjacent the circular wall of the shell of a refining tower which while providing a distributed and free overflow, from one tray to the next lower tray, obviates the necessity of an intricate and difficult construction.

A particular object of the invention is to provide an improved downcomer involving an inclined deflector and conductor which may be installed at the overflow side of a bubble tray without the use of elements conforming to the curvature of the shell wall and without extensive welding.

A further object of the invention is to provide an improved downcomer wherein a single transverse truss or support may be employed for supporting one side of a bubble tray and for suspending the downcomer.

Another object of the invention is to provide an improved downcomer including an inclined plate connected to adapters, whereby the plate may be readily and efficiently secured in place without complicated components or the use of intricate structures.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a view of a portion of a refinery tower, partly in elevation and partly in section, showing a downcomer constructed in accordance with the invention.

Fig. 2 is a partial plan view of one of the trays and the downcomer.

Fig. 3 is an isometric view of a portion of the tray and downcomer.

Fig. 4 is an enlarged transverse sectional view of a portion of a tray and its downcomer.

Fig. 5 is a composite isometric view of separated elements of a portion of a tray and its downcomer, and

Fig. 6 is a partial transverse sectional view of a tower having a downcomer therein.

This application is filed as a continuation-in-part of my co-pending application filed May 15, 1944, Serial No. 535,612.

In the drawings, the numeral 10 designates a cylindrical tank which forms the shell of a re-

2

fining tower illustrated as being of the bubble tower type. A portion only of the tank has been shown and said tank may be of any desired diameter and height, although usually the diameter will be relatively small. A plurality of transversely-extending trays A are disposed at spaced intervals or elevations throughout the height of the tank in the usual manner and the quantity of trays is subject to variation according to the size 5 of said tank and its particular use. Since the present invention involves only the mounting of the trays, only two of said trays have been shown and additional trays (not shown) are normally disposed above and below the trays which have 10 been illustrated. It is pointed out that this invention is not to be limited to use with the particular tower shown and described herein, because it may be successfully used in any refining column or tower having super-imposed trays or decks 15 mounted therein. Of course, the processing of the hydrocarbon fluid, which is conducted through the trays of the tower, forms no part of the present invention and any conventional method of operation may be employed.

Each tray A is supported within the tank by a substantially annular, flat ring 11 which is secured to the inside of the wall of the tank 10 by welding, or other suitable means and projects 20 radially and inwardly from said wall. A plurality of deck plates or floor sections 12, of stainless steel or other like weight material and preferably corrosion-resistant material, are supported upon medial transverse trusses 13 and upon transverse trusses or channel members 14 and 15 at each side, 25 all of which trusses extend across the tank in substantially parallel relation. It will be observed that the ring 11 does not extend entirely around the tank and may be referred to as a mutilated circumferential support. Each ring terminates 30 at the ends of the transverse truss 15, which ends may be welded or otherwise secured to the tank wall, and have their upper surfaces flush with the upper surface of the ring. It will be observed 35 from Fig. 1 that the trusses 14 and 15 are disposed in opposite relation with respect to opposite sides of the tanks, the truss 15 of the upper tray A being adjacent the left hand side of the tank, the truss 15 of the lower tray A being adjacent the right hand side of the tank. This arrangement provides a gap or space between the trusses 40 15 and the tank walls, and this space forms part of an overflow channel 16, which involves elements to be hereinafter described.

The particular construction of the floor 12 is 45 not involved in this invention, and it may include

50 55

sectional plates properly mounted on the trusses, and frictionally clamped on the ring 11 by means of clamps 17, such as are shown in my Patent No. 2,341,091, issued February 8, 1944; however, the invention is not to be limited to the floor construction so long as a floor is used which will cooperate with the elements hereinafter set forth.

In the ordinary operation of a refining tower, the liquids flow downwardly while the gasses flow upwardly. In order to form trays, a transverse weir is disposed transversely at one side of the floor, and a complementary weir 18 is likewise disposed at the opposite side of the floor. The weir 18 is formed of an angular member which is bolted on the floor 12 by means of bolts 20, which pass through the floor and the top of the channel-shaped truss 15. It will be observed that the floor has an extension 12' from the weir 18 to the ring 11, which is secured by the clamps 17. The opposite side of the floor 12 rests upon the flat top 21 of the channel-shaped truss 15.

The weir 18 is angular in cross-section, as is best shown in Figs. 4 and 5, and rests upon the truss with the outer face of its upright leg flush with the outer face of the truss. The bottom leg of the weir is offset upwardly at 22 so as to overlap the edge of the floor 12. The parts are secured together by bolts 23. When the upper tray A of Fig. 1 is filled with liquid, such as oil, to the upper edge of the weir 18, such oil will overflow into the channel 16.

The downcomer includes a downwardly extending deflector plate 24, which extends longitudinally of the truss 15, and is inclined toward the tank wall to co-act therewith in forming the channel 16. The plate has, at its top, a laterally directed flange 25, which underlies the relatively narrow base flange 26 of the truss 15. These flanges are secured together at spaced intervals by bolts 27. As is clearly shown in Figs. 1 and 4, the downcomer plate 24 overhangs the floor extension 12' of the next lower tray A, and while terminating a short distance above the floor extension, extends well below the upper edge of the weir 18, thus when liquid flows down the channel 16, it will fill the bottom thereof up to the upper edge of the weir 18 before overflowing into the lower tray, and thereby the lower end of the plate 24 will be immersed in such liquids and a gas tight seal will be provided.

For supporting and closing the vertical ends of the plate 24, an adapter 28 is provided at each end of the plate. As hereinbefore pointed out, the ends of the angular weir 18 abut the inner edges of the supporting ring 11 and the upright outer face of the weir lies flush with the radial edges of the adjacent supporting ring. The top flange of the plate 24 and the upper portion of said plate is cut out at each end as indicated at 30, as is best shown in Fig. 5, so as to form a gap wherein the adapter plate 28 may be inserted between the plate 24 and the outer face of the truss 15. The outer vertical edge of each adapter plate is welded or otherwise secured to the tank wall to form a gas tight joint. The adapter plate is formed with a vertical slot 31 for receiving the bolt 32 which passes through the truss 15 for securing the plate thereto. The plate 28 may be made in one piece, or the upper portion 28' thereof may be made separately, and its outer vertical edge welded to the tank wall flush with the plate 28. A slot 33 is provided in the member 28', for receiving a bolt 34 whereby the member may be secured to the upright face of the weir 18.

Each adapter plate is formed with an outwardly directed inclined boss 35, which may be pressed from the plate or offset in any suitable manner, and which provides a flat support for the overlapping ends of the downcomer plate 24. It will be observed that the plate 24 is flat from end to end transversely of the tower; thus, by means of the adapters 28 the plate may be supported at the proper angle and the edges of the adapters welded to the tank wall. While the downcomer plate 24 may be secured to the boss 35 in any suitable manner, it is preferable to attach the downcomer plate to the inner inclined edge of the boss by means of clamps 36 such as are shown in my Patent 2,341,091, supra, whereby said plate is made detachable. The plate 24 is formed near each end with horizontal slots 38' spaced upwardly of the plate at suitable distances, as is best shown in Fig. 5. These slots receive the bolts of the clamps 36 which latter overlie said slots and engage under the edges of the bosses 35. It is desirable to make all joints as tight as possible, and to pack the same in any suitable manner, so that gas cannot escape therebetween.

The hereinbefore described construction makes it possible to produce an entire tray with its downcomer from light-weight material without sacrificing strength or rigidity. By the use of light-weight material, the cost and time of manufacture are decreased, and assembly facilitated. The assembly which is built around the traverse truss 15 is unique and readily assembled. The various elements may be readily detached when necessary, and the cutting of difficult curves and the making of intricate structures is avoided. The adapters are very important, because they permit latitude in matching and securing the parts together, as well as providing a convenient means of assembly.

It is pointed out that no bubble tower has the same internal diameters at different elevations. These towers have general inside diameters of from 10 to 15 feet and in making up the sections it is impossible not only to make the internal diameter of each section, identical, but to get them truly circular. Thus a section may be out of round and its internal diameter may be as much as an inch, either less or greater, than the next section. For these reasons the adapter 28 and the friction clamps 36 are very important. Since the plate 24 overlaps the inclined flat boss 35 of the adapter, said adapter may be slid laterally to compensate the varying internal diameters or the vertical edge of the adapter may be inclined to lie flush with a slightly inclined tank wall. The friction clamps 36 not only permit these adjustments, but also provide expansion and contraction joints.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. The combination with a cylindrical tank having a plurality of spaced trays extending transversely across the interior thereof, of a vertical downcomer for each tray including, a plate depending from each tray and having its lower end terminating adjacent the tray therebelow, an angular adapter for securing the vertical ends of the plate to the cylindrical wall of the

tank, the adapter comprising an upright plate having one longitudinal edge secured to said cylindrical wall and being bent upon itself to provide a boss overlapping, receiving and supporting said inclined plate, whereby said adapter seals off between the inclined plate and the cylindrical tank wall, and means for clamping the overlapping portions of the plate and boss together, whereby the adapter may be laterally adjusted.

2. The combination with a cylindrical tank having a plurality of spaced trays extending transversely across the interior thereof, of a vertical downcomer for each tray including, a flat plate depending from each tray and having its lower end terminating adjacent the tray therebelow, an angular member for securing the sides of the plate to the cylindrical wall of the tank, the member having a vertical portion fastened to said cylindrical wall and a flanged portion underlying and supporting said plate, whereby the member seals off between the plate and the cylindrical tank wall, and means for clamping the overlapping portions of the plate and boss together, whereby the adapter may be laterally adjusted.

3. In combination, a curved tank wall, a transverse truss channel-shaped in cross-section having its ends attached to the tank wall, a weir angular in cross-section extending longitudinally on said truss, means for securing the weir on the truss, said truss and weir being spaced from the tank wall between their ends, a downcomer plate inclined downwardly toward the tank wall and attached to the truss, the downcomer terminating short of the tank wall at its ends, adapters at each end of the plate secured to the tank wall and having angular portions underlapping the ends of the plate for closing the vertical spaces between the tank wall and the ends of the plate, and clamps fastening the overlapping portions of the plate to the angular portions of the adapters.

4. As a sub-combination in a downcomer, an adapter including an upright plate and an inclined boss struck from the plate at one side thereof and having a flat face.

5. A downcomer including, an inclined transverse plate having a laterally directed flange at its top and provided at each end with gaps, and adapters engaging in the gaps at the ends of the plate and having inclined bosses underlapping and secured to the end portions of the plate.

6. A downcomer including, an inclined transverse plate having a laterally directed flange at its top and provided at each end with gaps, adapters engaging in the gaps at the ends and having inclined bosses underlying the end portions of said plate, and clamps for attaching the plate to the adapter bosses, whereby the adapters may be laterally adjusted and the plate may undergo expansion and contraction.

7. A downcomer for refining tanks including, a transverse tray support, an inclined downcomer plate suspended from the support, separate adapters at each end of the plate, each adapter including an inclined portion onto which the plate overlaps and a portion having a substantially vertical outer edge, whereby it may be secured directly to the wall of a tank, and friction clamps connecting the overlapping portions of the plate and adapters.

8. A downcomer for refining tanks including, a transverse tray support, an inclined downcomer plate suspended from the support, separate adapters at each end of the plate, each adapter having an inclined portion onto which the plate overlaps and an angular portion integral therewith having a substantially vertical edge, whereby it may be secured directly to a tank wall, and friction clamps connecting the overlapping portions of the plate and adapters.

HANS C. GLITSCH.
